(57) **CLAIM**

The ornamental design for a lid with carry loop, as shown and described.

DESCRIPTION

FIG. 1 is a top front perspective view of a lid with carry loop showing our new design;

FIG. 2 is a top rear perspective view of the lid with carry loop shown in FIG. 1;

FIG. 3 is a front view of the lid with carry loop shown in FIG. 1;

FIG. 4 is a rear view of the lid with carry loop shown in FIG. 1;

FIG. 5 is a left side view of the lid with carry loop shown in FIG. 1;

FIG. 6 is a right side view of the lid with carry loop shown in FIG. 1;

FIG. 7 is a top view of the lid with carry loop shown in FIG. 1; and,

FIG. 8 is a bottom view the lid with carry loop shown in FIGS. 1.

The broken lines are shown for the purpose of illustrating environmental structure and parts of the article that form no part of the claimed design.

1 Claim, 8 Drawing Sheets
